WINDING DEVICE FOR USE IN PERMANENT
WAVING

William H. Cooper, Washington, D. C.

Application January 30, 1933. Serial No. 654,292

10 Claims. (Cl. 132—33)

This invention relates to an improved curler for use in connection with a permanent wave machine and more particularly relates to the mandrel having an improved hair engaging lock at one end and an improved construction of winder adapted to be applied to the mandrel and coil a lock of hair about the mandrel when rotated and slid longitudinally upon the mandrel.

Another object of the invention is to provide the mandrel with a hair engaging lock having an improved type of hair gripper and means for moving the gripper into and out of position to firmly grip the lock of hair engaged through opposed recesses formed in the body portion or housing of the lock.

Another object of the invention is to provide a hair engaging lock having associated therewith a pad which will serve as a shield and prevent the scalp from being burned when the mandrel and lock are heated.

Another object of the invention is to so construct the winder that when this winder is in use, a closure for a passage through which a lock of hair is moved into position to extend through the winder will be automatically moved to an opened position to permit the passage of the lock of hair into the winder and then automatically moved to a closed position.

A still further object of the invention is to so construct the closure that as the lock of hair is wound about the mandrel, the coil of hair upon the mandrel will serve to firmly hold the closure in a closed position.

Another object of the invention is to provide a winder consisting of a few number of parts which are simple in construction and very strong and not liable to break or get out of order when in use.

With these and numerous other objects in view, my invention consists in the novel features of construction, combination and arrangement of parts as will be hereinafter referred to and more particularly pointed out in the specification and claims.

In the accompanying drawings forming a part of this application:

Figure 1 is a side elevation of the improved hair curler;

Figure 2 is a sectional view taken transversely through the mandrel along the line 2—2 of Figure 1 and looking toward the hair lock as indicated by the arrows;

Figure 3 is a view similar to Figure 2 showing the hair gripper moved to a gripping position instead of the opened position shown in Figure 2;

Figure 4 is a sectional view taken diametrically through the hair lock along the line 4—4 of Figure 2;

Figure 5 is a sectional view showing the elements of Figure 4 separated from each other; 60

Figure 6 is a sectional view through the hair lock taken along the line 6—6 of Figure 4 with the hair gripper in the opened position;

Figure 7 is a perspective view showing a portion of the mandrel and the elements forming 65 the hair lock taken apart;

Figure 8 is a side elevation illustrating the manner in which the lock of hair is initially engaged through the improved winder, forming part of 70 this curler;

Figure 9 is a view similar to Figure 8, showing the lock of hair partially wound about the mandrel;

Figure 10 is a view showing the lock of hair completely wound about the mandrel and held by 75 the winder;

Figure 11 is a sectional view taken transversely through the mandrel and winder along the line 11—11 of Figure 8;

Figure 12 is a sectional view taken transversely 80 through the mandrel and winder along the line 12—12 of Figure 10;

Figure 13 is a view showing the winder in longitudinal section and a portion of the mandrel in elevation, the view being taken along the line 85 13—13 of Figure 14;

Figure 14 is a sectional view taken transversely through the winder and mandrel along the line 14—14 of Figure 13;

Figure 15 is a view similar to Figure 13 but 90 taken along the line 15—15 of Figure 14;

Figure 16 is a perspective view of the closure forming part of the winder;

Figure 17 is a side elevation of the improved winder, but showing a slightly modified construction; and 95

Figure 18 is a sectional view taken along the line 18—18 of Figure 17.

In describing the invention, I shall refer to the drawings in which similar reference characters 100 designate corresponding parts throughout the several views and figures. This improved hair curler has a mandrel 1 consisting of a metal rod of any desired length and diameter and at its inner end the mandrel carries a lock by means of which 105 it is to be removably fixed to a lock of hair 2 which is to be wound about the mandrel and form a tight coil 3 held in a firmly wound condition about the mandrel while it is subjected to heat during a curling operation. The lock has upper and lower 110

walls 4 and 5 which together with a marginal wall or collar 6 define a housing and referring to Figure 4, it will be seen that the upper wall is formed integral with the mandrel and spaced 5 from the inner end thereof whereas the lower wall 5 consists of a separate disk fitted upon the reduced inner end 7 of the mandrel. This reduced inner end of the mandrel is upset after the disk or wall 5 has been applied and serves as a rivet 10 to firmly hold the lower wall in place. The marginal wall or collar 6 is applied before the wall 5 is set in place and has an inwardly extending annular flange 8 which fits between marginal portions of the upper and lower walls. A portion of 15 the flange 8 is extended inwardly to form an annular lip 9 terminating in tongues 10 and 11 at its end and by referring to Figure 6, it will be seen that the portion of the flange 8 above the lip 9 gradually reduces in width toward the tooth 20 or tongue 10 to form a cam surface 12. Opposed recesses 13 and 14 which open through their margins are formed in the walls 4 and 5 so that hair may be engaged through the locks and ends 25 of the collar 6 terminate in such spaced relation to each other that when the collar is in the position shown in Figure 2, the open ends of the recesses will be exposed. When, however, the collar is turned about margins of the upper and lower walls to the position shown in Figure 3, a portion 30 of the collar will extend across the open outer ends of the recesses and serve as a closure for the same. In view of the fact that the wall 4 is formed with an upstanding marginal flange 15, the circumferentially extending edge face of this wall 35 will be comparatively deep and provide a good bearing surface which will prevent excessive wear and also guide movement of the collar and permit it to be easily turned.

It is desired to protect a person's scalp from 40 danger of being burned by accidental contact with the collar or other portions of the lock when the mandrel and lock are heated during a curling operation and, therefore, there has been provided a shield 16 consisting of a disk cut from 45 felt or other suitable material. This shield fits flat against the under face of the lower wall 5 with its marginal portions overlapping the lower edge 8 of the collar 6 and is held in place by a screw 17 passed through an opening 18 formed 50 centrally of the shield and screwed into a threaded socket 19 formed in the lower end portion of the mandrel axially thereof. This shield will, therefore, be firmly held in place by a removable fastener having its head countersunk within the 55 central portion of the shield and by referring to Figure 7 it will be seen that the shield has a portion cut therefrom to form a recess 20 which registers with and corresponds in dimensions to the recesses 13 and 14.

60 When this mandrel is in use, a lock of hair after being passed through the registering recesses 13, 14 and 20, is to be very firmly gripped in order to securely lock the mandrel to the lock of hair. In order to do so, there has been provided a hair gripper or arm 21 which is curved longitudinally in order to extend circumferentially of the housing across the registering recesses when in the closed position shown in Figure 3. This hair gripper or arm has one end 65 portion thickened to form a heel 22 of such thickness that it will fit snugly between the upper and lower wall of the housing and through this heel is formed an opening 23 to receive a screw 70 24 engaged through aligned openings 25 and 26 formed in the upper and lower walls and serv-

ing as a pivot pin about which the gripper swings from the opened position shown in Figure 2 to the closed position shown in Figure 3. At one end the heel is formed with a shoulder 27 for engagement by the tongue 10 and at its other end, the 80 heel is formed with a shoulder 28 for engagement by the tongue 11. Referring to Figures 2 and 3, it will be readily seen that when the collar 6 is turned from the position shown in Figure 3 towards the position shown in Figure 2 and the 85 end of the collar carrying the tongue 10 moves across the recesses, the tongue 10 by contacting with the shoulder 27 will serve to swing the gripper or arm 21 about its pivot to the opened position and retain it in this open position. A lock of hair may then be moved into place within the registering recesses of the housing and pad or shield after which the collar may be rotated in a reverse direction. As the collar moves in 90 this direction, the cam surface 12 will act against the arcuate edge of the gripper to swing the gripper inwardly towards a closed position and the lock of hair will be forced towards inner ends of the recesses and very firmly gripped. The collar moves across outer ends of the recesses to 95 close the same and firmly hold the gripper in a hair gripping position. In case a very small lock of hair is engaged through the recesses of the lock or the device is not in use, the collar may be fully turned to the position shown in Figure 3 in 100 which position, the tongue 11 will engage the shoulder 28 and prevent further rotation of the lock in this direction. Therefore, rotation of the collar about the housing will be controlled and the gripper will be positively moved to an opened 105 or closed position.

The winder illustrated in Figures 8 through 18 and by means of which the lock of hair is to be wound about the mandrel to form the coil 3 is formed of strong metal and has a tubular shank 29 having a skirt 30 carried by and projected from its inner end. The outer end portion of the shank is split as shown at 31 to permit the shank to frictionally grip the mandrel and yieldably resist movement of the winder upon the mandrel 115 when the device is in use. There has also been provided turning arms 32 projecting radially from the shank intermediate its length in order that the shank may be grasped and easily rotated about the mandrel.

Referring particularly to Figures 13 and 15, it will be seen that the skirt is in the form of a cup having a head at its inner end uniting this end of the cup to the shank and the annular walls of the skirt are formed with a longitudinally 120 extending passage constituting an entrance through which a lock of hair will be fed into the winder as shown in Figure 11 and having an extension 34 leading from one end of the entrance through the head of the skirt or cup circumferentially thereof. At one side of the entrance 33, there has been formed a flat surface 35 for directing a lock of hair inwardly into the winder and at the other side of this entrance, there has been formed a hinge ear 36 to which 125 are pivotally connected hinge ears 37 formed upon a closure 38. This closure is arcuate when viewed from either end as clearly shown in Figures 11, 14 and 16 and is extended beyond the hinge ears 37 to form a tongue or inner end portion which is snugly received in a seat 40 within the walls when the closure is in the closed position shown in Figure 12.

Referring to Figure 14, it will be seen that when the closure is shut, it is spaced slightly from 130

the marginal edge of the flat surface 35 in order to permit this flat surface to guide a lock of hair inwardly between its free edge and the free end of the closure. Therefore, the lock of hair may 5 move inwardly when the winder is initially applied and rotated as shown in Figure 11 and as it moves inwardly, the closure or shutter will be swung outwardly towards an open position. Marginal edges of the wall about the open end of the 10 skirt are bevelled as shown at 41 to permit the skirt to fit tightly about the lock of hair as it is wound about the mandrel by turning up the winder and force this hair tightly against the outer wall 4 of the lock. The lock of hair as it 15 initially moves into the winder through the entrance 33 extends toward the right as shown in Figure 8 to pass into the extension 34 and it will be retained in an upright position and properly guided into this extension by the upper end or 20 extension 42 of the closure which corresponds in height to the depth of the walls of the skirt but is of greater height than the portion of the closure forming the hinge ear and tongue 39. Attention 25 is also called to the fact that above the hinge ear 36 the wall of the skirt curves upwardly thereby defining a shoulder 34 serving to direct the lock of hair toward the left and retain the lock of hair in substantially a direction longitudinally of the mandrel as it passes through the 30 mandrel and is wound about the same to form the coil 3. After the lock of hair enters the skirt of the winder and moves circumferentially therein about the mandrel, it will engage the tongue or inner end portion of the closure and by so doing 35 force the closure to the closed position shown in Figure 12. This will confine the lock of hair and prevent it from slipping outwardly through the entrance as the winder is rotated about the mandrel. In view of the fact that the shank of the 40 winder has gripping engagement with the mandrel, it will be frictionally bound to the same and although it may be turned about the mandrel and may be slid longitudinally thereon, it will remain in a set position and serve as a binder to retain the lock of hair tightly wound about the mandrel and prevent it from slipping and uncoiling until the winder is manually removed after a curling 45 operation is completed. The winder illustrated in Figures 17 and 18 is similar in construction to the form previously described and corresponding elements are indicated by the same reference numerals. In this embodiment of the invention, the closure 44 has its inner end portion forming a tongue corresponding to the tongue 39 of the closure 38 but the outer portion of this closure 50 has its upper and lower edges extending parallel and both cut along straight lines. The upper edge of the closure extends in the plane of the upper edge of the inner tongue or end portion and the upper portion of the flat face 35 projects above the closure as clearly shown in Figure 17 and takes the place of the extension 42. The walls of the skirt are of an even thickness throughout their 55 depth instead of being formed with a flared mouth. The operation of this form of winder is the same as already described and referring to Figure 18, it will be seen that the lock of hair may enter the skirt or cup of the winder and after moving the closure to an opened position during 60 entry, will engage the tongue or inner end portion of the closure and swing the closure to a closed position as the lock of hair is wound about the mandrel.

From the foregoing description of the construction of my improved curler, the operation

thereof and the method of applying the same to use will be readily understood. It will be seen that I have provided a simple, inexpensive and efficient means for carrying out the objects of the invention and while I have particularly described the elements best adapted to perform the functions set forth, it is obvious that various changes in form, proportion and in the minor details of construction may be resorted to.

Having thus described the invention what is claimed is:

1. In a hair curler, a winder having a hair receiving portion formed with a passage for permitting movement of a lock of hair into the same, and a closure for said passage automatically moved out of and into closing relation to the passage by a lock of hair.

2. In a hair curler, a winder formed with a passage whereby a lock of hair may be engaged through the winder, and a closure mounted for pivotal movement into and out of closing relation to the passage by engagement with a lock of hair.

3. A winder for a hair curler comprising a shank to fit about a mandrel, an annular skirt at one end of said shank formed with a passage whereby a lock of hair may be engaged through the skirt, and a closure for said passage movable by a lock of hair into and out of a closed position.

4. A winder for a hair curler comprising a shank to fit about a mandrel, an annular skirt at one end of said shank formed with a passage whereby a lock of hair may be engaged through the skirt, and a closure for said passage pivotally mounted for movement into and out of closing relation to the passage, said closure having a tongue extending inwardly from its pivot for engagement by a lock of hair to hold the closure closed.

5. A winder for a hair curler comprising a tubular shank to fit about a mandrel, a skirt extending from one end of said shank and having an annular wall and a head at the inner end of the wall uniting the wall to the shank, said wall being formed with a longitudinally extending passage communicating with a slot extending circumferentially of the head, and a closure pivoted at one side of said passage for movement out of and into closing relation to the passage.

6. A winder for a hair curler comprising a tubular shank to fit about a mandrel, a skirt extending from one end of said shank and having an annular wall and a head at the inner end of the wall uniting the wall to the shank, said wall being formed with a longitudinally extending passage communicating with a slot extending circumferentially of the head, and a closure pivoted intermediate its ends to the skirt at one side of the passage, the outer end portion of the closure being adapted to extend across the passage to close the same and the inner end portion extending circumferentially of the skirt within the same for engagement by hair to close the closure.

7. A winder for a hair curler comprising a tubular shank to fit about a mandrel, a skirt extending from one end of said shank and having an annular wall and a head at the inner end of the wall uniting the wall to the shank, said wall being formed with a longitudinally extending passage communicating with a slot extending circumferentially of the head, and a closure pivoted intermediate its ends to the skirt at one side of the passage, the outer end portion of the closure being of a length to extend across the passage when closed, the inner end portion of the closure being of reduced thickness and forming a tongue.

extending circumferentially of the skirt and engageable by hair to move the closure to a closed position.

8. A winder for a hair curler comprising a tubular shank to fit about a mandrel, a skirt extending from one end of said shank and having an annular wall and a head at the inner end of the wall uniting the wall to the shank, said wall being formed with a longitudinally extending passage communicating with a slot extending circumferentially of the head, and a closure pivoted intermediate its ends to the skirt at one side of the passage, the outer end portion of the closure being of a length to extend across the passage when closed, the inner end portion of the closure being of reduced thickness and forming a tongue extending circumferentially of the skirt and engageable by hair to move the closure to a closed position, the wall of the skirt being formed with an internal recess receiving said tongue when the closure is closed and disposing the surface of the tongue flush with the inner face of the wall to permit smooth rotation of the skirt about hair coiled about a mandrel during a winding operation.

9. A winder for a hair curler comprising a tubular shank to fit about a mandrel, a skirt extending from one end of said shank and having an annular wall and a head at the inner end of the wall uniting the wall to the shank, said wall being formed with a longitudinally extending passage communicating with a slot extending circumferentially of the head, and a closure pivoted intermediate its ends to the skirt at one side of the passage, the outer end portion of the clo-

sure being adapted to extend across the passage to close the same and the inner end portion extending circumferentially of the skirt within the same for engagement by hair to close the closure, the outer portion of said closure when closed having its free end overlapping the wall of the opposite side of the passage from the pivotal mounting of the closure in spaced relation thereto and the portion of the wall overlapped by the closure being flattened to direct a lock of hair inwardly between the wall and closure.

10. A winder for a hair curler comprising a tubular shank to fit about a mandrel, a skirt extending from one end of said shank and having an annular wall and a head at the inner end of the wall uniting the wall to the shank, said wall being formed with a longitudinally extending passage communicating with a slot extending circumferentially of the head, and a closure pivoted intermediate its ends to the skirt at one side of the passage, the outer end portion of the closure being adapted to extend across the passage to close the same and the inner end portion extending circumferentially of the skirt within the same for engagement by hair to close the closure, the outer portion of said closure when closed having its free end overlapping the wall at the opposite side of the passage from the pivotal mounting of the closure in spaced relation thereto whereby a lock of hair may pass inwardly between the wall and closure and means being provided to engage a lock of hair passed through the skirt and direct the same longitudinally through the skirt during a winding operation.
